METHOD OF MAKING STENCIL CARDS

Eugene J. Lamb, Vestal, N. Y., assignor to International Business Machines Corporation, New York, N. Y., a corporation of New York

Application August 21, 1942, Serial No. 455,661

2 Claims. (Cl. 101—128.4)

This invention relates to a stencil card of the kind which can be used in card controlled accounting and tabulating machines.

One object of the invention is to provide a card of this type in which the stencil window is protected while the card is passing through a punch or other card handling machine, such as a sorter, interpreter, verifier, or tabulating machine. In its preferred form, the stencil card is constructed so that the stencil can be cut either before or after the card has been punched, or run through other card handling machines.

Another object of the invention is to improve the quality of the stencil.

Still another object is to provide a stencil card which protects the type and platen from injury in the stencil cutting operation.

Other objects of the invention will be pointed out in the following description and claims and illustrated in the accompanying drawing, which discloses, by way of example, the principle of the invention and the best mode, which has been contemplated, of applying that principle.

In the drawing:

Fig. 1 is a face view of a stencil card made in accordance with my invention, after punching and interpreting but before the cutting of the stencil.

Fig. 2 is a transverse section of the parts of which the stencil card is constructed, showing them in position for joining.

Fig. 3 is a perspective view of the stencil card with the front flap turned back into position for cutting the stencil.

Fig. 4 is a face view of a modified form of the stencil card.

As shown in Fig. 1, the body 10 of the stencil card has a window 11 within which the stencil will appear when the card is finished. The card is made of two plies 12 and 13 (Fig. 2) and a piece of stencil paper 14. The stencil paper is slightly larger than the window 11 and is positioned so that its margins will be bound between the two plies of the card when the plies are joined by adhesive. In each ply a similar area is partially cut out to form the window 11. In the embodiment shown in Figs. 1 to 3, this area is cut along the top, bottom and right sides but along the left side the plies are only perforated to form a weakened line 17 about which the two cut out flaps 15 and 16 can turn as on a hinge. While the flaps are shown tilted out in Fig. 2, for better visibility, actually they remain in place during the manufacture of the card.

The preferred method of handling a stencil 55

card of this kind is to send it first through the perforator, or equivalent machine, to record that part of the information which is to appear upon the card in the form of perforations, or other sensible indicia. Fig. 1 shows by way of example a check addressing card for addressing dividend checks. The card has been passed through the perforator and the stockholder's number, the number of shares, and the amount have been 5 perforated. The card has then been passed through an interpreter which has printed the same information at the top of the card under control of the perforations previously made. During these operations, the flaps 15 and 16 have 10 remained in place in the window, covering the stencil paper and protecting it from injury by the feed rolls of the card handling machines, which, for this reason, do not require special adjustment to handle the stencil cards. The 15 card may be passed through any other machines controlled by its perforations while in the condition shown in Fig. 1, such as collators, sorters, verifiers, tabulators, etc.

When the stencil is to be cut, the front flap 25 16 is turned back on its hinge 17, to the position shown in Fig. 3, the rear flap 15 remaining in place. The flap 16 may, in fact, be torn off at this time, if all of the operations in the card handling machines have been finished. In the 30 stencil cutting operation, the flap 16 performs two important functions. It improves the quality of the stencil letters, since it acts as a filler between the platen and the stencil window, which would normally be spaced from the platen by 35 the thickness of the rear card. It also prevents the type which cut the stencil letters from damaging a rubber platen or from being injured against a metal platen.

It is possible to reverse the sequence of operations, first cutting the stencil with the card in the condition shown in Fig. 3, then closing the front flap and passing the card through the perforator and other card handling machines.

Fig. 4 shows a modification in which the window areas of the plies are cut along all four sides 45 20, but not at the four corners 21. The uncut corners hold the window flaps in place until they are to be removed for cutting the stencil, or use of the card in stencil printing. Since these flaps, 50 once broken out, cannot be restored to their original condition, the punching and other card handling operations are necessarily carried out before the stencil cutting, with this type of card.

While there have been shown and described and pointed out the fundamental novel features

of the invention as applied to two modifications, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. The method of making a two-ply stencil card for use in card controlled machines, which comprises partially cutting registering windows in the two plies, joining the plies, with stencil material between them covering the window area, making a record on the card in the form of sensible indicia, with the material of both plies within the window area in place, and cutting the stencil

with the material of the front ply within the window area removed from the window area and the material of the back ply within the window area in place.

2. The method of making a two-ply stencil card for use in card controlled machines, which comprises forming window flaps in the two plies by weakening the plies along a hinge line and cutting through the plies around lines defining a window area adjacent the hinge line, joining the plies with the stencil material between them covering the window area, punching the card with both flaps covering the window area, and cutting the stencil with the front flap turned back and the rear flap covering the window area.
